[57] CLAIM

The ornamental design for a housing for insulation blowing machine, as shown and described.

DESCRIPTION

FIG. 1 is a three quarter front perspective view of a housing for insulation blowing machine embodying my new design.

FIG. 2 is a rear elevation thereof.

FIG. 3 is a side elevation of the opposite side from that shown in FIG. 1, the handle being shown as broken away for ease of illustration.

The interior, as seen from the top, follows the contours of the outer surface and the bottom is flat and unornamented.
